UNITED STATES PATENT OFFICE

2,438,142

AIR CUSHION PAD FOR GUNSTOCKS

William H. Brower, Clark, S. Dak., assignor of
one-half to Watson C. Brower, Clark, S. Dak.

Application February 22, 1945, Serial No. 579,297

1 Claim. (Cl. 42—74)

1
All guns shot from the shoulder of a person have upon being shot a recoil, or "kick," and the purpose of this invention, named herein as an air cushion pad for gun, is to resist, absorb and reduce to a minimum such recoil, or "kick."

It is a further object of the invention to provide a pad of the character indicated which can be expeditiously applied to or removed from the stock of a gun, and when applied, the means for securing it in place has been found efficient and satisfactory in use.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 is a view in side elevation of a fragment of a gunstock, with a pad embodying the invention applied;

Figure 2 is an end view thereof;

Figure 3 is a vertical sectional view of the pad and a fragment of the gunstock; and

Figure 4 is a sectional view of the gunstock and pad on the line 4—4 of Fig. 1.

In these drawings 1 denotes a gunstock to which the recoil pad is attached, it being shown that the said recoil pad comprises a boot 2 which fits the outer surface of the stock at the shoulder end thereof. The boot is tubular and has its outer end crimped as at 2a to form a bead which is joined to a resilient pad 3 by being lodged in an indentation 4 formed externally of the collapsible pad around a peripheral wall 5 joining front and rear walls 6 and 7, respectively. The wall 7 has external surfaces 8 and 9 at the upper and lower ends thereof to engage the shoulder of the operator when the gun is in position for firing. The resilient cushion is formed of air-proof flexible material shaped substantially to the shape of the butt end of a gun, and it will be noted that wall 6 has an apertured boss 10 through which an air tube 11 projects, by which air is forced through

2
suitable means such as a valve 10' from a nipple 12 on the end of the tube 11. It will be obvious that when air is forced under pressure into the pad, it will yield or expand and the rigidity of the cushion will be determined by the air pressure.

The boot is preferably made of rubber which will stretch to a degree that it will adapt itself to gunstocks of different sizes, but when released, will closely bind or contact the surfaces of the gunstock and frictionally retain the pad in place. The gunstock will be provided with a suitable recess, such as 13, for the reception of the air connections, and when the boot is attached to the pad, preferably by a vulcanizing process, the assembled parts will be strong and durable as well as comparatively inexpensive to manufacture and maintain.

I claim:

20 A pad for the butt of a gun-stock comprising an air cushion having a front wall for contacting the gun-stock and a rear wall, a curved peripheral wall joining said other two walls, said curved wall being circumferentially indented, and a resilient boot having an open end adapted to snugly fit over the gun-stock, the other end of the boot being securely and permanently connected throughout its periphery to the curved wall of the pad in the indentation thereof.
